US00D815075S

(12) **United States Design Patent** (10) **Patent No.:** **US D815,075 S**
Kwak et al. (45) **Date of Patent:** **** Apr. 10, 2018**

(54) **NETWORK TERMINAL**

- (71) Applicant: **Samsung Electronics Co., Ltd.**, Suwon-si (KR)
- (72) Inventors: **Jihee Kwak**, Seoul (KR); **Kyu-Cheol Kim**, Seoul (KR); **Eun-ae Lee**, Seoul (KR); **Moonjung Jang**, Gunpo-si (KR)
- (73) Assignee: **SAMSUNG ELECTRONICS CO., LTD.**, Gyeonggi-Do (KR)
- (**) Term: **15 Years**
- (21) Appl. No.: **29/566,997**
- (22) Filed: **Jun. 3, 2016**

(30) **Foreign Application Priority Data**

Feb. 19, 2016 (KR) 30-2016-0007763

(57) **CLAIM**

The ornamental design for a network terminal, as shown and described.

DESCRIPTION

FIG. 1 is a side perspective of a network terminal, showing our new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines illustrating portions of a network terminal form no part of the claimed design.

1 Claim, 7 Drawing Sheets
